ELASTIC YARN AND METHOD OF MAKING

Philip Ernest Frank Clay, Radcliffe-on-Trent,
EnglandApplication October 11, 1949, Serial No. 120,684
In Great Britain November 11, 1948

11 Claims. (Cl. 57—163)

1

This invention is for improvements in elastic fabrics and elastic yarns for use therein; the expression "elastic fabrics" as used herein means and includes fabrics incorporating elastic (India rubber threads); the India rubber may be cut or extruded as desired.

Some of the difficulties experienced in the manufacture of elastic fabrics are set out in the specification of my prior U. S. Patent No. 2,220,213 and in that specification means are described for overcoming these difficulties. These means consist in making a composite thread comprising an elastic thread in a substantially completely relaxed condition in conjunction with an inelastic carrier thread.

The method of making such composite thread consists in providing a supply of elastic thread in a state of complete relaxation (i. e. unstretched) in conjunction with a supply of carrier thread, withdrawing the threads simultaneously from their respective supplies in such manner as to maintain the elastic thread substantially in its fully relaxed condition and then uniting the two threads such as by wrapping them with an inelastic covering thread or by doubling them together. The carrier thread inhibits stretching of the elastic thread during the process of making fabric consisting of or incorporating the composite thread and after the fabric has been made the carrier thread is rendered inoperative such as by breaking it or by destroying it by chemical means. Fabrics produced in this manner are not liable to puckering or wrinkling but they possess the inherent disadvantage associated with relaxed untensioned rubber threads, namely, that when stretched they have a comparatively small contracting force.

By way of explanation it may be said that assuming one has an elastic thread ten inches in length when in a relaxed un-tensioned condition and one stretches it two inches so that it is now twelve inches in length and then relieves the tension it will contract to its original length of ten inches but the force of contraction is comparatively small. If now one stretches the same piece of elastic thread 100 per cent so that it is twenty inches and then extends it a further two inches and releases it, the contracting force contracting the thread from twenty-two inches to twenty inches will be very much greater than was the force of contraction which contracted it in the first instance from twelve inches to ten inches.

In certain types of fabrics it is highly desirable to have a strong contracting force when the fabric is subjected to tension in a direction to

2

stretch the elastic threads and the principal object of this invention is to provide fabrics of this type.

With this and other objects in view, the invention consists in a method of making elastic fabrics which consists in first stretching an elastic thread to a predetermined extent, retaining it in a stretched condition, thereafter applying by wrapping or otherwise one or more inextensible thread or threads to inhibit further stretch, introducing the composite thread so formed into the fabric and thereafter rendering the said inextensible thread or threads inoperative, it will, of course, be appreciated that the fabric preferably incorporates a plurality of such composite threads. The said inextensible thread or threads may be removed by chemical means, as by the treatment of the fabric with a solvent, and in the latter case said thread or threads may conveniently consist of soluble alginate yarn.

Further objects of the invention are to provide elastic yarn suitable for incorporation in elastic fabrics produced by the method aforesaid, and methods of production of such yarn.

25 In a preferred method of carrying the invention into effect, an elastic thread has applied to its exterior whilst the thread is stretched and under tension a clockwise and a counter-clockwise helical wrapping of threads which are so applied as to maintain the elastic thread under tension, that is in a stretched condition after the wrapping process has been completed. Machines of the general type disclosed in Patent Specification No. 2,220,213, may be utilised for this purpose but it will be appreciated that the elastic thread is not drawn from a loose supply in a relaxed condition but is drawn conveniently from a bobbin or the like in a tensioned condition, and in this condition is fed to two spaced 30 wrapping stations whereat the helical clockwise and counter-clockwise wrappings are applied. The wrapping threads are substantially inextensible threads and may be of cotton or other suitable textile. The composite thread, hereinafter referred to as the basic thread, is conveniently wound on to a bobbin and, as stated, in such composite thread the elastic thread is maintained in a stretched or tensioned condition by the applied wrappings. During the process of applying 35 these wrappings the thread may be stretched to the limit of its elasticity or to any other desired extent, the degree of stretch being dependent upon the purposes for which the basic thread is to be used.

55 It will be appreciated that in the basic thread

so made the elastic thread is not necessarily extended to the same degree as that to which it was extended during the wrapping process (in other words it may contract to some extent after being wrapped) but the essential point is that the basic thread when made does consist of a central core of elastic thread which is in a stretched or tensioned condition and the wrapping threads limit the degree to which the elastic thread is allowed to contract. Threads so made would be quite unsuitable for use in the manufacture of many types of fabrics for the reason that during the process of incorporation of such threads into the fabric they would be subjected to tension and therefore would stretch and later relax with the result that the finished fabric would be of less width than the fabric as made, whilst furthermore there would be a great tendency for wrinkles or puckers to be produced in the fabric. In accordance with the present invention, therefore, the basic thread is so treated as to inhibit further stretch during the process of manufacturing the fabric.

A preferred method of inhibiting such further stretch consists in applying to the basic thread whilst in a relaxed or untensioned condition at least one further wrapping, and preferably two or more further wrappings of thread or threads which is/are applied so as to inhibit further stretch and which after the composite thread so formed has been incorporated in the fabric is rendered inoperative such as by being destroyed by chemical means. The thread or threads used for the further wrapping or wrappings are substantially inextensible and if more than one further wrapping is applied one moiety of such wrappings may be applied in a clockwise direction and the remainder in a counter-clockwise direction.

The foregoing and other objects of the invention will be more fully understood from the following description, given by way of example and with reference to the accompanying drawings wherein:

Figure 1 illustrates an elastic core thread prior to wrapping.

Figure 2 shows diagrammatically the elastic core thread in course of wrapping.

Figure 3 shows a portion of a completed composite thread.

Figure 4 is an elevation of certain wrapping apparatus employed in one method according to the invention.

Figure 5 is a sectional elevation of another portion of apparatus employable in the exercise of the invention.

Figure 6 is an elevation of modified wrapping apparatus.

Figure 7 is a fragmentary view of a portion of elastic fabric incorporating threads as shown in Figure 3.

Figure 8 is a view similar to Figure 7, wherein the stretch-inhibiting wrapping of the elastic threads is removed, and

Figure 9 is a similar view of a piece of fabric as shown in Figure 8 when stretched laterally.

In the manufacture of an elastic yarn according to the invention, primarily for incorporation in elastic fabrics, the elastic or India rubber core thread, whether cut or extruded, is first stretched as shown in Figure 1 of the drawings, wherein the unstretched length of a portion of core thread is indicated by the bracket A and a length to which the thread may be stretched in exercising the invention is indicated by the

bracket B, the latter length being less than a greater length to which the portion of core thread is capable of stretching conveniently and without breakage or loss of resilience, as indicated for example by the extent of the chain dotted portion C of Figure 1.

Figure 2 shows a first stage of forming the composite yarn according to the invention wherein there has been applied to an elastic core thread 10 a first, closely-pitched, clockwise, helical wrapping 11 of a non-elastic thread, for example a cotton or other suitable textile thread, and thereafter a superimposed, similar but counterclockwise wrapping 12.

The basic yarn thus produced comprises the elastic core and the two superimposed wrappings of thread which are so closely pitched as to prevent the return of the elastic core to its initial unstretched length. It will be appreciated that when released from the tension applied to it by the wrapping apparatus such basic thread may contract to some extent by compression of the two helical wrappings upon themselves under the pull of the elastic but essentially such wrappings will by their grip on the elastic core limit such contraction and ensure that the core is maintained in a stretched condition.

Figure 3 shows a portion of the basic thread after undergoing the final yarn production stage wherein there have been applied over the outer helical wrapping of the basic thread two further, wide-pitched helical wrappings 13 and 14 of an inextensible thread, respectively clockwise and counter-clockwise, which serve while they remain upon the basic thread to inhibit further stretch thereof.

Convenient apparatus for producing the basic thread according to Figure 2 is shown in Figure 4. A reel 14 of India rubber or like core thread 10 is driven by means of a drum 15 the periphery of which engages the core thread upon the bobbin 14 to control the take-off speed. The core thread is withdrawn from the reel 14 by means of a roller 16 in such a manner as to effect a constant rate of stretch of the elastic, the rollers 16 and 15 being conjointly driven at mutually regulated speeds by speed correlating means indicated at 17 so that the peripheral speed of the roller 16 is greater, by say about 50%, than the peripheral speed of the roller 15.

In travelling from the bobbin 14 to the roller 16 the core thread passes first through a tube 18 carrying reel 19 of wrapping thread which is applied about the core by a fier 20, the tube 18 with the reel and fier being driven frictionally by means of a belt 21 from a pulley 22 on a shaft 23 and constituting in known manner a first wrapping station. After the application of the first wrapping 11 at this station the thread passes through a second wrapping station including a rotating tube 24 carrying a reel of wrapping thread 25 and a fier 26 whereby the second wrapping thread 12 is applied over the first wrapping 11. The tube 24 is driven frictionally by means of a belt 26 from a pulley 27 on a shaft 28, and in order to ensure that the successive wrappings 11 and 12 are applied one in clockwise and the other in counterclockwise direction the shafts 23 and 28 may be connected by any suitable means for ensuring their rotation in opposite directions, and for effecting any required mutual adjustments of speed, such as a gear box indicated at 29. After the application of the second wrapping thread 12 the basic thread thus constituted passes while still under tension round the reel 16 with

the surface of which it is engaged by a jockey roller 30, and thence by way of suitable guides to a receiving bobbin 31.

The basic thread may be allowed to relax under the restraint exerted on the contraction of the elastic core thread by the applied wrappings 11 and 12, and for this purpose the receiving bobbin 31 may be driven, for example by means of another drum such as 15 bearing on the surface of the basic thread as it is wound on the bobbin, and rotated at a suitable peripheral speed. The basic thread is then in a desirably relaxed condition for the following stage.

Alternatively, the basic thread may be wound upon a bobbin such as 31 or equivalent means, while still in a stretched condition, subsequently being relaxed prior to the application of further wrappings, for example by means of apparatus such as that diagrammatically shown in Figure 5.

In such apparatus the bobbin 31 is mounted on a vertical spindle and thread is withdrawn therefrom by means of a roller 32 with the periphery of which the thread is engaged by a jockey roller 33, and is passed on to a loose pile 34 wherein any superficial tension of the core, beyond that retained in it by the wrappings 11 and 12, is released. The basic thread is then taken from the pile 34 in its relaxed condition for the application of stretch inhibiting threads 13 and 14 (Figure 3) by means of apparatus such for example as that already described with reference to Figure 4, but wherein the speeds of the take off and winding rollers corresponding to rollers 15 and 16 are adjusted to be equal in order to avoid further stretching of the thread. Moreover in such further windings the linear speed of the thread is greater in relation to the rotational speed of the wrapping elements at the wrapping stations in order to apply the threads 13 and 14 with a very much wider pitch or angle of helix relative to that of the threads 11 and 12 as indicated in Figure 3, so that the length of each turn of the threads 13 and 14 is as long as possible consistent with avoidance of slip and said threads 13 and 14 are well disposed to take the strain of any tension subsequently applied to the elastic yarn as in a fabric forming operation.

In another alternative, stretch-retaining wrappings 11 and 12, and further stretch inhibiting wrappings 13 and 14 may be successively applied to the core thread in one continuous operation by means of apparatus such for example as that shown in Figure 6. The apparatus here shown in effect comprises two sets of apparatus as described with reference to Figure 4, superimposed on one another, and parts corresponding and functioning similarly to those of Figure 4 are indicated by like reference numerals. After the application of the stretch retaining wrappings 11 and 12 as shown at the two lower wrapping stations the basic thread thus formed passes upwards through two further wrapping stations the first of which comprises an assembly 35 of tube, thread reel and flier driven by a belt 36 from a pulley 37 on a shaft 38 and the second of which comprises an assembly 39 of tube, thread reel and flier driven by a belt 40 from a pulley 41 on a shaft 42. The required correlation of speeds and directions of rotation of the shafts 28, 38 and 42 is affected by further means such as gear means indicated at 43, 44. While the wrappings 11 and 12 are advantageously applied one clockwise and the other counter-clockwise, and similarly the wrappings 13 and 14, as shown in Figures 2 and 3, it is not necessary that

the wrapping 13 should be applied in the opposite direction of rotation to that of wrapping 12, in which case drive reversing means may be eliminated from the means indicated at 43, though the latter may comprise speed adjusting means such as to secure a lower rate of rotation of the wrapping assemblies 35 and 39 relative to the linear speed of the basic thread.

From the wrapping station 39 the composite thread, now having the form indicated in Figure 3, passes around the tension roller 16 to a reel 45. Since the elastic yarn is now both prevented from contracting by virtue of the wrappings 11 and 12 and prevented from stretching to a greater extent than that applied by means of the rollers 15, 16, by virtue of the wrappings 13, 14, the application of subsequent tension or lack of tension in further operations is immaterial.

The composite yarn produced as above described may be employed in the manufacture of elastic fabrics in any desired manner. For example, composite threads 46 may be introduced as weft threads in a knitted warp fabric as shown in Figure 7. Since in the manufacture of the fabric the composite threads 46 are both prevented from contracting and inhibited from further stretch by their various wrappings, they continue in a substantially relaxed state and the fabric produced as shown in Figure 7 will retain its width as it issues from the knitting apparatus, without puckering.

A succeeding stage in the production of the fabric consists in the removal from the elastic threads 46 of the stretch inhibiting threads 13 and 14, for example by submitting the fabric to chemical treatment whereafter the finished fabric assumes the appearance indicated in Figure 8, being prevented from puckering laterally by the stretch retaining wrappings 11 and 12 of the elastic thread, but now free to be stretched laterally as indicated in Figure 9. The fabric as shown in Figure 8 still retains the width at which it was manufactured in the knitting apparatus, and is devoid of wrinkles or puckers. Further, since the elastic threads are in a controlled stretched condition when lying as shown in Figure 8, considerable force is required to stretch them, and the contracting force exercised by the elastic threads when stretched as shown in Figure 9 and tending to restore the fabric to the condition shown in Figure 8, is considerably greater than would be the case were the elastic threads initially in an unstretched condition.

The threads 13 and 14 which are wrapped on the exterior of the basic thread may be of any suitable material. They may, for example, be of alginate or they may be of wool but they are essentially of a material different from that of which the fabric is made and are of such a nature that they can be destroyed by chemical action (calgon is a suitable solvent for alginate) which action has no deleterious effect on the remaining threads incorporated in the fabric including those threads 11 and 12 which were wrapped around the elastic core thread in the initial stages of stretch-retaining wrapping to produce the basic thread.

A further advantage of threads produced in accordance with this invention over threads of the type described in Patent Specification No. 2,220,213, is that threads in accordance with this invention are considerably smaller in cross sectional area and consequently more threads per unit of length may be introduced into the fabric.

The wrapping threads applied to the basic threads can be of comparatively small size so that they increase only very slightly the cross sectional area of the basic thread whereas in the method of the said prior specification the cross sectional area of the composite thread is substantially increased by the inclusion of the carrier thread which is subsequently rendered inoperative.

I claim:

1. The method of making elastic yarn comprising stretching an elastic thread to a predetermined extent, applying at least one close-pitched helical wrapping of thread to said stretched elastic thread to retain it in a stretched condition and thereby produce a basic thread, and associating externally with the basic thread thereby produced an inextensible thread to inhibit further stretch, said inextensible thread being removable or destructible by means harmless to the thread of said close-pitched helical wrapping.

2. The method of making elastic yarn wherein an elastic thread is stretched to a predetermined extent, the initially stretched elastic thread is retained in a stretched condition by applying thereto superimposed clockwise and counter-clockwise close-pitched helical wrappings of thread, applying at least one wide-pitched helical wrapping of an inextensible thread to inhibit further stretch, said inextensible thread being removable or destructible by means harmless to the thread of said close-pitched wrappings.

3. The method of making elastic yarn according to claim 1 wherein the inextensible thread is associated with the basic thread by being wrapped with a wide pitch therearound.

4. The method of making elastic yarn according to claim 1, wherein the close-pitched helically wrapped thread is inherently substantially 40 inextensible.

5. The method of making elastic yarn according to claim 1, wherein the basic thread has applied to it at least two further wide-pitched wrappings of inextensible thread, one moiety of said wide-pitched wrappings being applied helically clockwise and the remainder of the said wrappings being applied helically counter-clockwise.

6. The method of making an elastic yarn according to claim 1, wherein the inextensible thread is associated with the basic thread by

being wrapped with a wide pitch therearound and the basic thread is completely relaxed prior to and during the application thereto of said wide-pitched wrapping of inextensible thread.

5 7. The method of making elastic yarn according to claim 1, wherein the inextensible thread is associated with the basic thread by being wrapped with a wide pitch therearound and the basic thread is fed to and drawn from at least 10 one wrapping station in a relaxed state by means of bobbins rotated at equal peripheral speeds for the application thereto of said wide-pitched wrapping of inextensible thread.

15 8. An elastic yarn comprising an elastic thread held in stretched condition by at least one helical wrapping of close-pitched textile thread, and inhibited from further stretch by at least one further helical wrapping of wide pitched thread of a material removable as by chemical means that is harmless to said close-pitched wrapping.

20 9. An elastic yarn comprising an elastic thread retained in stretched condition by superimposed clockwise and counter-clockwise close-pitched helical wrappings of thread, and inhibited from further stretch by at least one further wide-pitched wrapping of an inextensible thread which is removable by chemical means that is harmless to said close-pitched wrapping.

10 10. An elastic yarn according to claim 9, having at least two of said further wide-pitched wrappings, whereof one moiety is applied helically clockwise and the remainder helically counter-clockwise.

30 11. An elastic yarn according to claim 8, wherein said wide-pitched helical wrapping is composed of a yarn, such as alginate yarn, which is removable by a solvent.
